EXPANSION TOOL

Foarde Thompson, Dallas, Tex.

Application September 18, 1943, Serial No. 502,935

5 Claims. (Cl. 254—77)

This invention relates to expanding tools and it has particular reference to such a tool designed to facilitate the application of insulating material to tanks, pipes and other curved or rounded surfaces.

The principal object of the invention is to provide means through which much time and labor is saved by dispensing with the practice of stretching sheets of insulating material by hand preparatory to securing them in place and substituting therefor the method afforded by the present invention which enables the operator to quickly and efficiently draw the confronting ends, sides or edges of the material together in position for securing in any conventional manner.

Another object of the invention is to provide a tool of the character specified consisting of an operating handle, to which is pivotally and adjustably attached a curved arm, each having on their operative ends a head provided with interchangeable or replaceable teeth for engagement with the material to be stretched or expanded and by proper actuation of the handle, the two heads are brought towards each other to impose tension on the material.

Still another object of the invention is to provide means for latching the handle and arm in adjusted positions if and when desired in stretching material other than insulating sheets, such as netted or woven fabric or the like so that one or both hands may be free for tying the contracted edges of the material handled.

With the foregoing objects as paramount, the invention has further reference to certain features of accomplishment, to become manifest as the description proceeds, taken in connection with the accompanying drawing, wherein:

Figure 1 is a perspective view of a tool constructed to the present invention.

Figure 2 is a detail perspective view of one of the toothed heads, with portions broken away.

Figure 3 is a similar view of the companion head whose parts are separated.

Figure 4 is a perspective view showing one form of application of the invention, and

Figure 5 is a slightly modified form of the invention in which the parts are capable of being locked in adjusted positions.

Heretofore, the general method employed for contracting insulating sheets onto the surfaces of tanks, conduits, pipes and the like consisted of drawing the sheets tight by hand. As a result, the material, usually expanded metal on which heat resisting material is applied, is not properly tensioned and further, much time

which could otherwise be conserved, is expended in this work.

Accordingly, and with more detailed reference to the drawing, numeral 10 denotes a handle on one end of which there is provided a cross-head 11 or other means of gripping the same, while its opposite end carries a toothed head 12.

The head 12 is preferably made in sections, one consisting of the head proper while the other is comprised of a cleat, conforming to and lying in a recess *a* transversely across the lip of the head 12. The two parts are held together by means of bolts 14. Jointly in the cleat 13 and the base of the recess *a* of the head, a series of depressions *b* are made to accommodate teeth 15, which are equi-distantly spaced, as shown in Figure 1.

The teeth 15 are curved at their outer ends to a position at substantially right angles to the bodies thereof to better engage the insulating material 16 (Figure 4) and further, in order to hold the teeth against rotative displacement in their sockets *b*, the inner ends of the teeth are bent into L-shape to conform to the similarly shaped portions of the depressions *b*. Obviously, other methods may be adopted with equal results to hold the teeth against rotation but that described and shown is preferred in view of its simplicity and effectiveness.

30 Connected pivotally to the shank of the handle 10 is a curved arm, consisting of parallel members 17.

It is preferred that the pivotal connection between the handle and arm be capable of adjustment along the axis of the handle to shorten and lengthen the working range between these elements. With this in view, a series of relatively spaced apertures 18 are provided in the handle, corresponding to similar apertures 18a in the arm, as shown. Obviously, by connecting the arm to the aperture, by means of pin 19, the operating range of the tool is at its maximum. Conversely, the lowest position minimizes the range. The apertures 18a in the arm

40 provide further adjustment similarly without changing the relative movement between the operative ends of the arm and handle. A stop 20 is interposed between the members 17 of the arm to limit the relative displacement of the arm and handle.

Mounted on the free ends of the members 17 of the curved arm is another toothed head 21. This head is also made up of separable parts, each of which has corresponding recesses or depressions *c* to jointly receive teeth 22. The two

conforming sections of the head 21 are held together by means of bolts 23.

As in the head 12 of the handle, the teeth 22 of the head 21 are required to be held against displacement inasmuch as they do not have intermediate bends as do the teeth 15 and rotation is of no consequence. As a means to prevent axial displacement, heads 24 are provided on the teeth 22 which are received in conforming parts of the recesses c, as shown in the cut-away portion of Figure 2.

It is apparent from the foregoing that when the teeth 15 of the head 12 are engaged in the interstices of the material 16 on one edge, with the teeth 22 of the head 21 similarly engaged on the confronting edge of the work material, movement of the handle 10 away from the arm 17 will tend to cause the heads to advance upon each other, thereby imposing tension upon the body of the material 16 surrounding the cylindrical object 25. Obviously, the tension imposed depends upon the pressure applied to the handle 10. After the two edges of the insulating sheet have been brought into contiguity, a suitable fastening means may be applied.

In some cases such as in stretching chicken wire or other woven fabric, it may be desired to secure the handle and arm in relatively contracted positions so that both hands may be used for tying or for other purposes. As a means to accomplish this, the structure shown in Figure 5 is provided and consists of a lever 26, pivoted at one end to an ear 27, formed on the head 28 with its opposite end free and extended between the two curved and parallel members forming the arm 29. The lever 26 has along one edge a series of ratchet teeth 30 which are relatively engageable with a stationary dog 31, situated between the members of the arm 29.

The lever 26, being loosely positioned, will move away from the dog 31 as the arm and handle are actuated to move their respective heads to any contracted position. To latch the members, it is simply necessary to move the lever 26 so that a selected one of its teeth 30 will engage behind the dog 31 and will be thus held to prevent relative expansion of the arm and handle. The tension of the material itself will provide the pressure which holds the parts in latched relationship.

Manifestly, the construction shown and described is capable of some modification and such modification as may be considered as falling

within the scope and meaning of the appended claims is also considered to be within the spirit and intent of the invention.

What is claimed is:

- 5 1. An expansion tool including a handle and a curved arm pivoted adjustably adjacent one end to the shank of said handle, a head composed of separable sections secured at the opposite end of said arm, a head also carried by said handle in opposed relationship with said first head and likewise composed of separable sections, a transverse series of relatively parallel teeth replaceably mounted in each of said heads and means for securing said head sections together.
- 10 2. A tool of the character described including a handle, a curved arm having adjustable pivotal connection adjacent one end to the shank of said handle, a sectional head mounted on the opposite end of said arm, a series of relatively parallel teeth removably mounted in and extending from said head, a head also mounted on the end of said handle, a plurality of parallel and curved teeth in said latter head and means for holding said curved teeth against rotation in said head.
- 15 3. A tool for expanding insulating material in mounting comprising a handle and a curved arm having a series of aligned apertures corresponding to aligned apertures axially in said handle for selective pivotal connection between said handle and arm, a head on the ends of said handle and arm in opposed relationship, a plurality of teeth in each of said heads and means to effect removal and replacement of said teeth.
- 20 4. A tool for mounting insulating sheets and the like comprising a handle and an arm connectable pivotally at one of a variety of positions adjacent one end to corresponding positions axially along the shank of said handle, a head also carried by said arm, a plurality of relatively parallel teeth removably mounted therein and means to secure said teeth in their respective head.
- 25 5. A tool of the character described including a handle and an arm adjustably pivoted adjacent one end to selective positions along the shank of said handle, a head on corresponding ends of said handle and arm, each having a transverse series of work engaging teeth therein in parallel relationship and means pivoted to the head of said handle and cooperating with means carried by said arm to secure said arm and handle in selectively adjusted positions on the work.

FOARDE THOMPSON.
